UNITED STATES PATENT OFFICE.

LILLIAN Z. GUNN, OF CHICAGO, ILLINOIS.

DESIGN FOR A PIN-HOLDER.

59,588.

Specification for Design.

Patented Nov. 8, 1921.

Application filed March 10, 1921. Serial No. 451,310. Term of patent 3½ years.

To all whom it may concern:

Be it known that I, LILLIAN Z. GUNN, a citizen of the United States, residing at Chicago, in the county of Cook and State of Illinois, have invented a new, original, and ornamental Design for Pin-Holders, of which the following is a specification, reference being had to the accompanying drawing, forming part thereof, wherein is exhibited in perspective a pin holder showing my new design.

I claim:

The ornamental design for a pin holder as shown.

LILLIAN Z. GUNN.
